ASSIGNORS TO THE MEASUREGRAPH COMPANY, OF ST. LOUIS, MISSOURI, A COR-
PORATION OF MISSOURI.

FLOATING SHEAR CONTROL FOR PRESSURE ROLLERS.

1,415,501.

Specification of Letters Patent.

Patented May 9, 1922.

Application filed May 3, 1920. Serial No. 378,480.

To all whom it may concern:

Be it known that we, JOHN L. WHEELER and EDWIN A. REED, citizens of the United States, residing in the city of St. Louis, 5 State of Missouri, and in Maplewood, in St. Louis County, and State of Missouri, respectively, have invented new and useful Improvements in Floating Shear Controls for Pressure Rollers, of which the following 10 is a specification.

This invention relates to cloth measuring or cost computing machines. The indicating mechanism of such machines is advanced by pulling the fabric to be measured past a 15 measuring roller, the rotation of which is communicated to the indicating mechanism. There is usually provided a presser roller which co-operates with the measuring roller to hold the fabric against the measuring 20 roller and thereby cause the rotation of the measuring roller by the fabric. The presser roller is held away from the measuring roller when the fabric is being introduced and positioned in the machine to take a 25 measurement; as soon as the fabric is properly positioned the presser roller is then let down against the fabric to hold the same against the measuring roller. In positioning the fabric in such a machine, the accuracy of 30 the measurement depends upon whether the forward edge of the fabric is properly aligned with the marking means, for marking the point at which the measured piece must be cut off. It is evident that if the 35 forward edge of the fabric is carried beyond the point where it should be, the machine will not measure the full quantity of fabric that is sold, thereby occasioning a loss to the retailer. The general object of this 40 invention is to provide means for insuring the proper alignment of the forward edge of the fabric before the measuring operation commences; and to provide simple means located in line with the marking means, for 45 controlling the operation of the presser roller before starting the measuring operation.

Further objects of the invention will appear hereinafter.

50 The invention consists in the novel features and in the general combination of parts to be particularly described hereinafter, all of which contribute to produce a simple and efficient cloth measuring or cost

computing machine. A preferred embodiment of my invention will be particularly described in the following specification, while the broad scope of my invention will be pointed out in the appended claims.

In the drawing,

Figure 1 is a side elevation partly broken away, illustrating a machine embodying my invention; this view shows the parts in their normal position with the presser roller raised and held away from the measuring 65 roller;

Figure 2 is a view similar to Figure 1, but showing the marking lever depressed as it would be in the operation of marking or notching the edge of the fabric after a measurement has been made;

Figure 3 is a vertical section taken on the line 3-3 of Figure 1;

Figure 4 is a side elevation showing details of the construction of a latch which 75 constitutes a feature of the invention;

Figure 5 is a plan of the latch shown in Figure 4 and indicating how this latch may be guided on the framing of the machine;

Figure 6 is a side elevation of the movable member which constitutes a part of the marking means and which may be operated to control the presser roller.

Referring more particularly to the parts, 85 the machine illustrated comprises a casing 1 in the upper wall of which windows 2 are provided, through which charts 3 are visible for indicating the length or cost of the goods measured (see Fig. 3). The lower 90 portion of the casing is provided with a gap 4 through which the fabric is pulled across the upper face of a measuring roller 5. Above this measuring roller 5 and co-operating with it there is provided the usual 95 presser roller 6, which is so mounted that it may be moved against the measuring roller or held raised away from the same. For this purpose the presser roller 6 is mounted in a presser roller frame 7 comprising an 100 arbor 8, the ends of which are mounted on pivots or gudgeons 9 in the frame of the machine. In the measuring operation the fabric passes through the casing of the machine in the direction of the arrow in Figure 105 3; the left hand wall 10 of the machine as viewed in Figure 3, is provided with an opening 11 adjacent to which the marking

means is located. This marking means is for the purpose of marking the edge of the fabric at the point where it is to be cut off after a measurement has been taken. The 5 marking means is preferably in the form of shears including a hand-operated marking lever 12 carrying a blade 13; when the lever 12 is actuated by means of a thumb plate 14 running in a slot 15 in the side wall 10 of the casing (see Fig. 1), the knife 13 will mark the edge of the fabric. Suitable means may be provided to co-operate with the knife 13 to attain this effect. Substantially in alignment with the marking means, I provide 15 a hand-actuated part, or movable member 16 which is mounted to move in a substantially vertical plane and this movable member is connected by suitable means with the presser roller frame 7 for controlling the 20 operation of the presser roller. The movable member for controlling the presser roller is preferably in the form of a floating knife or lever 16 Fig. 6 which carries a blade 17 co-operating with the other knife or blade 25 13. Co-operating with this floating knife or lever I provide means which may be controlled by the marking lever 12 automatically, so that when the marking lever is 30 actuated the floating lever 16 will become locked against movement, thereby enabling the blade 17 to co-operate with the knife or blade 13. But the marking lever 12 is normally held elevated by a coil spring 18 and when in this position the floating lever 16 35 may be freely operated. Any suitable connection may be provided between the movable member or floating lever 16 and the presser roller frame 7 for controlling the same. In the present instance the presser 40 roller frame is provided with a laterally projecting arm 19 which projects through an opening 20 in a side frame plate 21 (see Fig. 1). When the lever 12 is depressed, a projection 22 on the edge of this lever engages the arm 19 and forces it down, thereby 45 extending a spring 23 which is attached to the presser roller frame and normally exerts a force upon the frame tending to force the presser roller down upon the measuring 50 roller. I provide suitable latching means for latching the arm 19 down when it has been depressed by the lever 12, and this latching means preferably consists of a slide or slide plate 24 (see Fig. 4). This slide is suitably 55 guided on the frame plate 21, for which purpose the frame plate may be provided with openings 25 (see Figs. 1 and 5) and the ends of the slide plate are off-set laterally so as to be received in these guide openings and so that the off-set inner end 26 of the slide plate is guided on the vertical edge of a transverse vertical frame plate 27 (see Fig. 5). In a similar manner the outer off-set end 28 of this plate is guided across the 60 65 vertical edge of a frame plate 29. The lower

edge of this slide is provided with a vertical notch 30 which will receive the arm 19 when the plate is disposed in its extreme position toward the right, that is to say, when the presser roller is in contact with the measuring roller, this arm 19 lies in the slot. When the arm 19 is depressed to raise the presser roller, as soon as the arm passes below a shoulder 31 which is formed in the side of the notch 30, the latch or slide 24 will be 70 pulled toward the left by a coil spring 32 one end of which is attached to a pin carried by the slide and the other end of which is attached to a pin 33 on the inner side of the frame plate 21; in this way the latch will 75 operate automatically to hold the arm down and thereby hold the presser roller away from the measuring roller. In order to enable the floating lever 16 to control this latch I simply provide the floating lever 16 80 with an upwardly extending arm 34 terminating in a rounded head 35 which engages the inner end of the latch or slide. The floating lever 16 is normally held elevated by means of a coil spring 36 attached to the 85 upper end of the arm 34. This lever is provided with a tail 37, the lower edge of which is normally held against a stop-pin 38 projecting from the side of a bracket 39 which carries a common pivot 40 which supports 90 both the levers 12 and 16. The preferred construction of the floating lever is illustrated in Figure 6.

Suitable means may be provided for effecting the locking of the movable member or 100 floating lever 16 to prevent the same from moving when the marking lever 12 is being operated. For this purpose I prefer to provide a locking means in the form of a locking member 41 which may consist of a 105 slide mounted to slide on a horizontal face 42 on the bracket 39, being guided thereupon by means of a slot 43 in the member 41 and a screw 44 in the bracket. A suitable connection is provided between the lever 12 and 110 this locking member which operates to move the locking member into engagement with the floating lever to lock the lever against movement. This connection may be in the form of a slot 45 formed in the lever 115 co-operating with a pin 46 on the side of the locking member or lock 41. The outer end of the locking member 41 has an upwardly projecting toe 47 having a rounded upper edge. When the 120 lever 12 is in its raised position the toe 47 is disposed toward the right and out of the path of movement of the floating lever 16, but when the lever 12 is depressed the pin-and-slot connection at 45 and 46 will slide 125 130 the lock 41 toward the left so that its toe 47 engages the lower edge, or moves into the path of the lower edge, of the floating lever, thereby locking the floating lever against movement.

It should be understood that the operator of the machine may move the floating lever 16 downwardly by applying the pressure of his fingers directly over the knife 17. In order to protect the fingers of the operator and to prevent them from coming in direct contact with the upper edge of the knife or blade 17, I provide a protector strip 48 (see Fig. 3), which may be attached to the inner face of the lever and is formed so that it projects over the upper edge of the lever 16 and above the edge of the blade substantially as shown in Figure 3.

In operating the machine it should be understood that the fabric is introduced while the presser roller 6 is held in an elevated position (see Fig. 3) the forward edge of the fabric being held between the thumb and the fingers of the operator. The fabric should be positioned with its forward edge substantially in alignment with the marking means, that is to say, in alignment with the lever 12. When the operator has aligned the fabric as suggested, he then presses down the movable member or floating lever 16; this operates the arm 34 to shift the slide or latch 24 and the slide releases the arm 19, whereupon the spring or springs 23 pull the presser roller down against the measuring roller. The operator then pulls the fabric through the machine. After the desired amount of fabric has been measured on the machine, the operator actuates the marking lever 12. As the marking lever moves downwardly it slides the locking member 41 inwardly (see Fig. 2), and locks the movable member or floating lever 16 against movement, thereby enabling its blade 17 to co-operate with the lever blade 13; as the lever 12 moves downwardly it depresses the arm 19 until it comes below the shoulder 31, whereupon the spring 32 moves the latch 24 to the left so as to hold the presser roller in its raised position.

It is understood that the embodiment of the invention described herein is only one of the many embodiments my invention may take, and I do not wish to be limited in the practice of my invention nor in my claims, to the particular embodiment set forth.

What I claim is:—

1. In a machine of the kind described, the combination of a measuring roller, a presser roller mounted to move toward or from the measuring roller and co-operating with the same, marking means for marking the fabric at the point where it is to be cut off, and including a hand actuated lever and a hand actuated part, the latter having locking means capable of co-operating with the lever to hold the hand actuated part against movement during the marking operation, and means for controlling the operation of the presser roller by said hand actuated part.

2. In a machine of the kind described, the combination of a measuring roller, a presser roller mounted to move toward or from the measuring roller and co-operating with the same, marking means including a hand-operated marking member for actuating the marking means, a knife carried thereby, a floating knife consisting of a lever carrying a blade to co-operate with the first named knife, means connecting the floating knife's lever with the presser roller for controlling the operation of the same, and automatic means for locking the floating knife's lever against movement when the hand-operated member is moved to actuate the marking means.

3. In a machine of the kind described, the combination of a measuring roller, a presser roller mounted to move toward or from the measuring roller and co-operating with the same, marking means for marking the fabric at the point where it is to be cut off, including a marking lever carrying a knife, and a presser-roller controlling lever carrying a knife co-operating with the first named knife, a locking member co-operating with said last named lever; and a connection between said marking lever and said locking member for moving the locking member into position to lock the said controlling lever when the marking lever is actuated.

4. In a machine of the kind described, the combination of a measuring roller, a presser roller mounted to move toward or from the measuring roller and co-operating with the same, marking means including a hand-operated marking member for actuating the marking means, a knife carried thereby, a floating member carrying a knife to co-operate with the first named knife, means connecting the floating member with the presser roller for controlling the operation of the same, a locking member mounted to co-operate with the floating member to lock the same against movement when the hand-operated marking movement is actuated, and a connection between the hand-operated marking member and said locking member for actuating the locking member to move the same into engagement with the floating member and hold the same against movement when the marking operation is taking place.

5. In a machine of the kind described, the combination of a measuring roller, a presser roller mounted to move toward or from the measuring roller and co-operating with the same, marking means including a hand-operated marking lever, a knife carried thereby, a floating lever carrying a knife to co-operate with the first named knife, means connecting the floating lever with the presser roller for controlling the same, a locking member movably mounted adjacent to the floating lever for locking the floating lever

against movement, and means for actuating the locking member by the marking lever to move the same into engagement with the floating lever.

5 6. In a machine of the kind described, the combination of a measuring roller, a presser roller mounted to move toward or from the measuring roller and co-operating with the same, a spring for forcing the presser roller 10 toward the measuring roller, a marking lever having means operating when the lever is actuated to raise the presser-roller, latching means for holding the presser-roller raised, a movable part co-operating 15 with the marking lever to mark the fabric at the point where it is to be cut off, means actuated by the marking lever for temporarily holding said last named movable member against movement when the marking 20 lever is actuated, and means actuated by said movable member for releasing the latching means to permit the presser-roller to move toward the measuring roller.

7. In a machine of the kind described, the 25 combination of a measuring roller, a presser roller, a presser roller frame carrying the presser roller and mounted to rock toward or from the measuring roller, a spring for rocking the presser roller frame in a direction 30 to force the presser roller against the measuring roller, a latch co-operating with said frame to hold the presser-roller away from the measuring roller, a marking lever carrying a knife, a floating lever carrying a 35 knife and co-operating with the marking lever to mark the fabric, means actuated by the marking lever for locking the floating lever when the marking lever is operated to mark the fabric, and means for releasing the 40 latch by the floating lever.

8. In a machine of the kind described, the combination of a frame including a frame plate, a measuring roller, a presser roller, a presser roller frame carrying the latter and 45 mounted to rock toward or from the measuring roller, a spring for pulling the presser roller frame in a direction to force the presser roller against the measuring roller, said presser roller frame having an arm, a 50 latch mounted to slide on said frame plate for engaging said arm to hold the presser roller away from the measuring roller, a marking lever carrying a knife, a floating lever, said levers having a common pivot 55 and said floating lever carrying a knife co-operating with the marking lever to mark the fabric, means actuated by the marking lever for locking the floating lever when the marking lever is operated to mark the fabric, 60 said floating lever having means for moving said latch to release the arm to permit the presser roller to come against the measuring roller.

9. In a machine of the kind described, the 65 combination of a frame including a frame

plate, a measuring roller, a presser roller, a presser roller frame carrying the latter and mounted to rock toward or from the measuring roller, a spring for pulling the presser roller frame in a direction to force the 70 presser roller against the measuring roller, said presser roller frame having an arm, a latch mounted to slide on said frame plate for engaging said arm to hold the presser roller away from the measuring roller, a 75 fixed pivot, a marking lever carrying a knife, and a floating lever carrying a knife both mounted on said pivot, a locking member mounted to slide under the floating lever and connected with said marking lever so as 80 to be moved by the marking lever into the path of movement of the floating lever, to lock the floating lever against movement, said floating lever having an arm engaging said latch to move the same and release the 85 arm to permit the presser roller to come against the measuring roller.

10. In a machine of the kind described, the combination of a measuring roller, a presser roller mounted to move toward or 90 from the measuring roller and co-operating with the same, a marking lever mounted to move in a substantially vertical plane to mark the fabric at the point where it is to be cut off, and a movable member mounted 95 to move in a substantially vertical plane substantially in alignment with the marking lever, and means for controlling the presser roller from said movable member.

11. In a machine of the kind described, 100 the combination of a measuring roller, a presser roller mounted to move toward or from the measuring roller and co-operating with the same, a marking lever carrying a 105 knife for marking the fabric at the point where it is to be cut off, a floating lever carrying a knife co-operating with the marking lever to mark the fabric, means actuated by the floating lever for controlling the presser roller, and a protector strip carried 110 by the floating lever adjacent to the knife and projecting up to enable the floating lever to be pressed down without exerting pressure on the edge of the knife.

12. In a machine of the kind described, 115 the combination of a measuring roller, a presser roller mounted to move toward or from the measuring roller and co-operating with the same, marking means for marking the fabric at the point where it is to be cut 120 off, and including a movable part, locking means capable of co-operating with said movable part to hold the same against movement in the marking operation, and means for controlling the operation of the presser 125 roller by said movable part.

In testimony whereof, we have hereunto set our hands.

JOHN L. WHEELER.
EDWIN A. REED.
